CLAMP FOR A LOOPED CABLE END

Daniel J. Foote, Wauwatosa, Wis., assignor to Master Lock Company, Milwaukee, Wis.

Filed Aug. 14, 1972, Ser. No. 280,329

Term of patent 14 years

Int. Cl. D8—99

U.S. Cl. D8—110

FIG - 1

FIG - 2

FIG - 4

FIG - 3

FIG. 1 is a front, top and side perspective view of a clamp for a looped cable end showing the design, the broken line showing of the cable being for illustrative purposes only;

FIG. 2 is an opposite end view of the clamp for a looped cable end;

FIG. 3 is a bottom view of the clamp for a looped cable end, the broken line showing of the cable being for illustrative purposes only; and

FIG. 4 is a sectional view of the clamp for a looped cable end taken on line 4—4 of FIG. 1 only with the cable omitted.

I claim:

The ornamental design for a clamp for a looped cable end, as shown and described.
